UNITED STATES PATENT OFFICE,

CATHRINE DUDGEON, OF NEW YORK, N. Y.

DESIGN FOR A NECKTIE.

SPECIFICATION forming part of Design No. 16,017, dated April 7, 1885.

Application filed February 11, 1885. Term of patent 3½ years.

To all whom it may concern:

Be it known that I, CATHRINE DUDGEON, of New York, county and State of New York, have invented and produced a new Design for 5 the Ornamentation of Neckties, of which the following is a specification.

My design relates to neckties of the kind in which two wing-shaped parts, usually termed "aprons," extend across a central part, and 10 one over the other.

I will describe in detail the ornamentation of a necktie embodying my design, and then point out the novel features in a claim.

A designates the neckband. B designates 15 a part extending downwardly from the neckband. C C' designate two wing-shaped portions or aprons, which extend from the sides of the part B and across the lower portion of the same. The apron C also extends across 20 the apron C'. Folds d extend downwardly from near the top of the part B in approximately parallel lines. Folds c c' are at the sides of the folds d, which are nearer the outer

edges of the aprons C C'. Plaits e in the folds c c' extend at approximate right angles to the 25 folds d toward the outer edges of the aprons C C'. The portions of the aprons C C' which are between the folds d and the part B project forward beyond the folds c c', the plaits e, and the part B. These projecting portions vanish 30 at their lower ends, or, in other words, become coincident with the lower portion of the aprons C C'.

What I claim as my design, and desire to 35 secure by Letters Patent, is—

The design for a necktie, consisting in the part B, aprons C C', folds d, forward-projecting portions upon the aprons C C' between the part B and the folds d, folds c c', and plaits e, extending at approximate right angles to 40 the folds d toward the outer edges of the aprons C C', substantially as shown and described.

CATHRINE DUDGEON.
